J. O. Edmunds

UNITED STATES PATENT OFFICE.

GEORGE McMANUS, OF NEW YORK, N. Y., ASSIGNOR TO EMBEE DISTRIBUTING COMPANY, OF NEW YORK, N. Y., A CORPORATION OF NEW YORK.

DESIGN FOR A SPINNING CARD.

•60,358.

Specification for Design.

Patented Feb. 7, 1922.

Application filed April 1, 1920. Serial No. 370,572. Term of patent 3½ years.

To all whom it may concern:

Be it known that I, GEORGE McMANUS, a citizen of the United States, residing at New York city, in the county and State of New York, have invented a new, original, and ornamental Design for a Spinning Card for Use in Playing Games, of which the following is a specification, reference being had to the accompanying drawing, forming part thereof.

The figure is a plan view of a spinning card for playing games showing my new design.

I claim—

The ornamental design for a spinning card as shown.

GEORGE McMANUS.

Witnesses:

RUDOLPH BLOCK,
E. MERRILL.
